TIME SWITCH

Harry R. Van Deventer, New York, N. Y., assignor
to Patent Engineering Corporation, a corpora-
tion of Delaware

Application June 14, 1932, Serial No. 617,116

11 Claims. (Cl. 200—37)

This invention relates to improvements in a time switch, and has for its object the provision of a switching mechanism that may be combined with a clock and used for a variety of purposes, such, for example, as when the device is connected with a radio receiver whereby a given radio program may be "set-up" ahead of time so that at the appointed time the clock will automatically operate the switching mechanism to connect the radio set in circuit for a predetermined time, after which the mechanism will automatically disconnect the set and stop the operation thereof.

A further object of the invention is the provision of a switching mechanism which can be used in place of the usual "on" and "off" switch now employed with radio sets and usually located on the set.

A further object is the provision of a time switch of simple and cheap construction in which the number of parts are reduced to a minimum, and which is adapted to be readily set without the necessity of opening the clock associated therewith.

The invention consists substantially in the construction, combination, location and relative arrangement of parts, all as will be more fully hereinafter set forth as shown by the accompanying drawing and finally pointed out in the appended claims.

By way of illustration the form of construction will be shown particularly suited for use with radio receiving sets and in the accompanying figures.

Figure 1 is a plan view of a time switch without the cover, case and crystal in place;

Figure 2 is a section on the line *a—a* of Figure 1 showing the cover, case and crystal in section, and

Figure 3 is an elevation of the complete device with the cover, case and crystal in place.

The clock movement per se may be of any suitable type and have any suitable form of driving mechanism. A suitable type is an electric clock comprising a synchronous motor driving the usual train of gears for operating the hour and minute hands. A second hand as shown in the drawing may be used but is not necessary to carry out this invention.

Referring to Figure 1, the gear ring 10 is rotatably mounted in the groove ring 11, the latter being mounted upon a ring of insulating material 12, secured to the base 13. This electrically insulates the gear and groove rings from the rest of the device.

The gear ring 10 has an inwardly projecting

arcuate portion 14 and by means of the hour knob 15 integral with pinion 16 rotatably mounted on stub shaft 17, the teeth of said pinion being in engagement with the teeth on the gear ring, the ring may be rotated so as to cause the contact portion 14 thereof to lie between any two hour markings on the dial of the clock, its position being determined by the pointer 18. When so set, the projection 14 is in position to be electrically contacted by the brush 19 carried by the hour hand 20 as it sweeps around its path over the clock dial 21.

The metal contact ring 22 is supported on posts (one of which is shown at 23 in Figure 2) insulatedly mounted on the ring 12, which may be of insulating material. Four arcuate segments 24, 25, 26 and 27 are insulatedly mounted on the ring 28 which may be of insulating material and are designed to be contacted by the brush 29, carried by the minute hand 30 as it sweeps around its path over the dial 21.

The segments 24, 25, 26 and 27 may be electrically connected to the ring 22 by means of switch buttons 31, 32, 33 and 34. Pressing one of these buttons inwardly completes the circuit from the segment (for example 25) in which it is mounted through to the ring 22, the button remaining in or out, as placed.

The conductor 35 connects to the groove ring 11 carrying the gear ring 10. The conductor 36 connects to the plate 22 or a suitable relay device 37 may be inserted anywhere in the circuit and the local contacts 38 of this relay may be used to control the circuits of the radio set or other device to be operated by the time switch, or the device to be operated may be serially included in circuit with the time switch and the source of current connected to 35, 36.

A circuit can now be traced from 35 to groove ring 11, to the gear ring 10, and the arcuate portion 14 thereof, to the contact 19 and through the hand 20, to the hand 30 and the contact 29 on the latter, to segment 24 and through button 31 therein (if it is pushed in) to the ring 22 and thence to the conductor 39 through relay 37 to conductor 36 thereby completing the circuit. The circuit will remain complete as long as the brush 29 is in contact with segment 24 but when, during the clockwise movement of the hand 30 the brush 29 rides off segment 24 the circuit will be opened and will remain open during the further operation of the clock for a 12 hour period.

To make this clear, it will be assumed that the time switch is "set up" in advance to close its contacts for a 15 minute interval beginning at 55

- 10 o'clock, the setting being as shown in Figure 1, and button 31, the "15 minute" button being pushed in. When contact 29 rides off the bottom end of the segment 24 the circuit through 5 the switch will be opened. As the clock operates during the period from 10:15 to 11:00, the contact 19 will gradually pass clockwise over the contact surface 14 and at 11 o'clock contact 19 leaves 14 and the circuit is broken at that point. 10 Obviously the closing of the contact between 24 and 29 which occurs each hour for a 15 minute period will not close the circuit through the device until hour hand 20 again causes 19 to contact with 14.
- 15 Assuming, however, that the next button 32 has been pushed in and thereby 25 is connected to 22, then the circuit will be closed for an additional 15 minutes, the time it will take brush 29 to sweep over the segment 25.
- 20 From the foregoing it will be seen that by properly setting the hour knob 15 and the corresponding buttons 31 to 34 inclusive that the time over which the switch will operate can be preselected for a period of 15, 30, 45 or 60 minutes or any combination of these 15 minute periods.

In order to provide means incorporated in this time switch for disabling the same so that it may be used as a manual switch, the switch button 40 is provided which is arranged to make contact between the ring 22 constituting one side of the switch circuit and the groove ring 11 constituting the other side of the circuit. By pushing this button 40 inwardly the circuit controlled by the hands of the clock is short-circuited. Obviously, when button 40 is used it is immaterial whether the knob 15 and the buttons 31 to 34 inclusive are in any certain position.

40 The switch mechanism may be covered by a suitable cover 41, preferably of insulating material, which supports the usual crystal 42 for the face of the clock. The cover 41 together with the base 13 may form the case of the clock, 45 the spring or electric motor therefor being enclosed thereby or mounted upon the base 15 and covered by a supplemental rear casing (not shown) in the usual manner.

Although the invention has been disclosed in connection with the specific details of preferred embodiments thereof it must be understood that such details are not intended to be limitative of the invention except in so far as set forth in the accompanying claims.

55 What is claimed is:

1. A time switch having a clock face and hands, contact members on said hands, a movable contact member positioned about said face and turnable about an axis and adapted to contact with a contact member on one of said hands for a predetermined time interval, a plurality of fixed contact members positioned above said face and adapted to contact with another of said contact members on another of said hands, and means for connecting one or more of said fixed contact members in series with all the contact members on said hands and in series with said movable contact member.

2. A time switch comprising a base supporting the face and hands of the clock and mechanism for driving the hands, a contact member insulatedly supported on said base and adjacent the path of travel of one of said hands and adapted to contact therewith, a plurality of fixed 70 contact members insulatedly separated and sup-

ported on said base and lying adjacent the path of travel of one of said hands and adapted to contact therewith, a plate adjacent said last members, means for connecting one or more of said last contact members to said plate, and conductors forming a circuit serially including said hands, contact members and plate.

3. A time switch having a face and hands, a gear ring insulated from said face and rotatably supported adjacent the periphery thereof, means for adjusting said ring, means for establishing contact between a portion of said ring and the hour hand of the switch, a plurality of contact members insulated from the aforesaid parts, and means for establishing contact between the minute hand of the switch and said last members.

4. In combination with a clock having a face, a movable contact member circumferentially shiftable about said face and having an inwardly extending arcuate portion adapted to contact with the hour hand of said clock during a portion of its travel over said face, a minute hand, and a plurality of arcuate contact members surrounding the path of travel of said minute hand and adapted to contact therewith during the sweep of said hand around the face of the clock.

5. In combination, a clock having a face and hands, a ring surrounding said face and circumferentially shiftable thereabout, said ring having an arcuate extension thereon extending inwardly toward the center of said face and adapted to contact on one of said hands, and a plurality of arcuate contact members overlying a portion of said ring and insulated therefrom and adapted to contact with one of said hands.

6. The combination as claimed in claim 5, wherein means is provided for manually connecting more than one of the contact members in an electrical circuit.

7. A time switch having a face, indicator hands extending radially of said face, arcuate contact members above said face adjacent the path of travel of said hands and adapted to contact therewith during the movement thereof, one of said members being circumferentially shiftable about the path of travel of said hands, and a circuit controlling switch mounted upon said switch having manual control means extending outwardly from the face of the time switch whereby all said contact members may be disabled.

8. A time switch having a face, indicator hands extending radially of said face, arcuate contact members above said face adjacent the path of travel of said hands and adapted to contact therewith during the movement thereof, one of said members being circumferentially shiftable about the path of travel of said hands, a circuit controlling switch mounted upon said time switch having manual control means extending outwardly from the face of the clock whereby all said contact members may be disabled, a case enclosing said contact members, means extending through said case for manually adjusting said movable contact member, and means extending through said case for connecting some of said contact members in circuit.

9. A time clock having a face and hour and minute hands, a contact member circumferentially shiftable in respect to said hour hand and adapted to contact therewith during the movement thereof across a pre-selected time interval 70 space on said face, and a plurality of fixed contact members permanently mounted on said clock and extending entirely around the path of travel of said minute hand and adapted to contact therewith for pre-determined intervals.

10. In combination with a clock having a face and hour and minute hands, a plurality of fixed contact members circumferentially positioned about the face of said clock and adapted to contact with one of said hands to complete a circuit through said hands in series for predetermined periods, a movable contact member adapted to contact with one of said hands and means turnable about an axis for varying the position of said last member relative to said hands and thereby varying the duration of the circuit completed therethrough.
11. A time switch having a face, a hand extending radially of said face, a spring contact member carried by said hand and extending outwardly therefrom, a segment positioned above said face adjacent the path of travel of said member and adapted to contact for a predetermined time therewith, said segment having a non-yielding surface adapted to definitely determine the length of dwell of said contact member thereon during the movement of said hand, a second hand extending radially of said face, a spring contact member carried by said last hand, a plurality of segments fixed in respect to said last hand adjacent the path of travel of said last contact member and adapted to contact for a predetermined time therewith, said segments having a non-yielding surface adapted to definitely determine the length of dwell of the last contact member thereon during the movement of said last hand, and means for connecting all of said contact members together.
15. A time switch having a face, a hand extending radially of said face, a spring contact member carried by said hand and extending outwardly therefrom, a segment positioned above said face adjacent the path of travel of said member and adapted to contact for a predetermined time therewith, said segment having a non-yielding surface adapted to definitely determine the length of dwell of said contact member thereon during the movement of said hand, a second hand extending radially of said face, a spring contact member carried by said last hand, a plurality of segments fixed in respect to said last hand adjacent the path of travel of said last contact member and adapted to contact for a predetermined time therewith, said segments having a non-yielding surface adapted to definitely determine the length of dwell of the last contact member thereon during the movement of said last hand, and means for connecting all of said contact members together.

HARRY R. VAN DEVENTER.
